UNITED STATES PATENT OFFICE.

PAUL ANSCHÜTZ, OF NEW YORK, N. Y., ASSIGNOR OF ONE-HALF TO GEORGE BICKELHAUPT,
OF NEW YORK, N. Y.

BOBBIN-CARRIER FOR SEWING-MACHINES.

No. 888,634.

Specification of Letters Patent.

Patented May 26, 1908.

Application filed June 22, 1905. Serial No. 266,617.

To all whom it may concern:

Be it known that I, PAUL ANSCHÜTZ, a citizen of the United States, residing in New York city, borough of Brooklyn, county of Kings, and State of New York, have invented certain new and useful Improvements in Bobbin-Carriers for Sewing-Machines, of which the following is a full, clear, and exact specification.

10 My invention relates to certain new and useful improvements in bobbin carriers. Its purpose is to do away with the necessity of using specially shaped bobbins upon which the thread must be wound before placing it in a sewing machine as is now the case in most double-thread machines.

15 By means of my present invention it is possible to use ordinary spools of thread as they are commercially sold in the trade by 20 means of a specially designed spool or bobbin carrier which I have produced, and thus a great saving of time and labor is possible.

25 Other features of my invention include the provision of a suitable tension device to such 30 a carrier and of automatic spool ejecting means therefor, when the carrier is opened for the purpose of replacing a spool from which the thread has been used.

35 While my invention is adaptable to many kinds of machines it is particularly useful in connection with the machine shown in Letters Patent No. 766,130 granted to me, July 26, 1904, and in the drawing I have illustrated it as applied to a machine of this type.

40 In these drawings Figure 1 represents a perspective view of so much of the loop-forming mechanism of the sewing machine as is necessary to show the general application of my present invention, the spool carrier being shown in dotted lines for the sake of clearness. Fig. 2 shows a perspective view of one form of spool carrier and Fig. 3 a top view thereof. Fig. 4 is a perspective view of a modified form of my invention and Fig. 5 a top view of the device of Fig. 4. Fig. 6 is a perspective view of still another form of my device, and Fig. 7 an end elevation of Fig. 6. Figs. 8 and 9 show reverse sides of still another form of my invention. Fig. 10 is an inverted plan of the device of Figs. 8 and 9. Figs. 11 and 12 are end elevations thereof looking in different directions, and Fig. 13 is a view of a slightly modified form of the device of Fig. 9 showing the 55 spool retainer open and the spool ejector.

Figs. 14, 15 and 16 are side, top and end views respectively of still another form of my invention, and Fig. 17 is a similar view to Fig. 15 but showing the spool carrier open. Figs. 18 and 19 are detailed views of the 60 spring for holding the spool retainer in place.

Similar numerals of reference indicate like parts in all the drawings.

As will be readily seen, my spool carrier or case comprises a thread guiding ring or 65 frame 1, part of the peripheral edge of which is bifurcated and formed into ridges 2, 2 as shown in Figs. 3, 5, etc. The channel formed by these ridges is provided for the passage of the loop-taker 3, and loop-spreader 4, which are in every way similar to like parts in the machine of my patent before mentioned, and therefore neither they nor their operation in the machine need be more particularly described herein.

70 The thread guiding ring is pear-shaped, slightly flattened upon one side, that it is larger in cross section nearer one end than the other, although the opposite sides of the pear-shaped portion are not symmetrical, 75 one being somewhat flattened, and this is particularly valuable as it affords the greatest compactness possible in a device which carries a full size spool of thread and yet permits of a comparatively small loop to pass it. 80 At one end of the ring, the thread guiding peripheral edge terminates in a ridge 16 which projects slightly therebeyond and also projects laterally from the side faces of said ring, said ridge serving in connection with 85 coöperating mechanism in the machine to always keep the ring in its proper position.

In the device shown in Figs. 2 and 3 the spool holder or retainer consists of a cylinder 5, which is pivoted at one end as at 6. In 90 this form the cylinder swings out at right angles and permits the spool to be inserted therein, and when so inserted and the retainer swung home, the rounded end of a spring 7, enters a recess 8, in the top of the cylinder and securely holds it in place.

95 Figs. 4 and 5 show a somewhat similar construction, but in this instance the spool retaining cylinder is pivoted at the center and swings upon such pivot so that the spool may be inserted at either end. In this form the retaining spring 7, contains an additional perforation 9 which permits of the passage of the pivot 6.

100 Figs. 6 and 7 show a further modification

of my device wherein the spool retainer 5 is provided with lugs 10 through which the pivot 6 passes, and in this construction the whole cylinder swings out at right angles as 5 is indicated in dotted lines in Fig. 7.

Figs. 8 to 13 illustrate a slightly modified form of my invention. In this type the ring or frame 1, is provided with a central recess or basket which corresponds to and fulfills 10 the purpose of the cylinder in the above described forms, and I have therefore characterized it as 5. One half of the basket or spool retainer is hinged as shown in Fig. 9, and this half can be swung open to permit the 15 insertion of a spool and when closed is held in this position by the spring arm 11, passing over the shoulder 12, as shown in Figs. 11 and 12. The spring arm 11 can usually be formed integral with the swinging portion of 20 the spool retainer as the metal will be found of sufficient elasticity to be sprung in place where it is rigidly retained.

In Fig. 13 I have shown the swinging portion of the retainer as provided with a projection 13 beyond the pivot and this is so shaped that upon the opening of the case the projection bears upon the back of the spool and throws it out of the case and acts as a spool ejector. When the case is closed it lies 30 inside the case and out of the way and does not interfere at all with the spool or thread.

The modified form of my device Figs. 14 to 17 inclusive, show a similar basket having a swinging portion or cover 5, but in this 35 form the cover is pivoted at the end instead of at the sides, and swings out as is shown in Fig. 17. A small lug 11 is provided on the swinging portion which engages a recess or shoulder 12 on the carrier and serves to hold 40 it in a closed position as shown in Fig. 11. I likewise provide a small spring tension 14 which for convenience I rivet or otherwise secure to the swinging cover as at 15, and before leading the thread from the spool 45 within the case to the machine it is passed under the said spring which serves to maintain a sufficient tension on the thread to prevent the thread unwinding therefrom, and which aids in the formation of a proper stitch.

50 It will be readily understood that many modifications and changes can be made in my invention from the particular forms shown without departing from the spirit thereof, and I do not limit myself to the particular features shown and described, but

55 What I claim and desire to secure by Letters Patent is,

1. A spool or bobbin carrier for sewing machines pear-shaped in cross section comprising a peripheral loop guiding ring having a bifurcated section extending part way around its circumference, a substantially cylindrical spool retainer positioned in said carrier and extending longitudinally thereof, the wall of said cylindrical retainer constituting

the sole support for the spool to be carried freely, said cylindrical spool retainer having a swinging side wall whereby access may be had for inserting or removing the spool and a spool ejector carried by the 70 swinging wall and adapted to throw out the spool upon the swinging of the side wall.

2. A non-revolvable spool or bobbin carrier, 75 pear-shaped in cross section comprising a peripheral loop guiding ring having a bifurcated section extending part way around its circumference, a substantially cylindrical spool retainer positioned in said carrier and extending longitudinally thereof, the wall of said spool retainer constituting the sole support 80 for the spool adapted to be carried thereby, a part of said cylindrical spool retainer being mounted for swinging movement to afford access thereto.

3. A non-revolvable spool or bobbin carrier 85 pear shaped in cross section comprising a peripheral loop guiding ring having a bifurcated section extending part way around its circumference, a substantially cylindrical spool retainer positioned in said carrier and 90 extending longitudinally thereof, the wall of said cylindrical spool retainer constituting the sole support for the spool adapted to be carried thereby, and said cylindrical spool retainer having a swinging side wall affording 95 access thereto, and a catch for retaining the swinging wall in place.

4. A non-revolvable spool or bobbin carrier 100 pear shaped in cross section comprising a peripheral loop guiding ring having a bifurcated section extending part way round its circumference, a substantially cylindrical spool retainer positioned in said carrier and extending longitudinally thereof, the wall of said spool retainer constituting the sole support 105 for the spool adapted to be carried thereby and said cylindrical spool retainer having a swinging side wall affording access thereto and terminating at its end in a spool 110 ejector.

5. A non-revolvable spool or bobbin carrier, 115 pear-shaped in cross section comprising a peripheral loop guiding ring having a bifurcated section extending part way around its circumference, a substantially cylindrical spool retainer positioned in said carrier and extending longitudinally thereof, the wall of said cylindrical spool retainer constituting the sole support for the spool adapted to be carried thereby, and said cylindrical spool 120 retainer having a swinging side wall affording access thereto.

In testimony whereof I have hereunto set my hand in the presence of two subscribing witnesses.

PAUL ANSCHÜTZ.
